COMBINATION ROLL AND INTER-
CHANGEABLE WHEEL

Pearl M. Hiles, Dayton, Ohio, assignor to The
Standard Register Company, Dayton, Ohio, a
corporation of Ohio

Application July 5, 1941, Serial No. 401,224

15 Claims. (Cl. 197—133)

This invention pertains to pin type strip feeding devices for progressively advancing strips of material having therein successions of longitudinally spaced feed holes and more particularly to a roller wherein a pin wheel unit may be interchangeably positioned in any one of a plurality of different axial positions.

For illustrative purposes, but with no intent to unduly limit the scope or application of the invention, it is herein illustrated and described as applied to a platen roller for a writing or imprinting apparatus, tabulator or computing machine, or to a feed roll for an autographic register or analogous mechanisms wherein one or more strips of record material are to be progressively advanced past a legend receiving position and prescribed areas thereof periodically registered with each other and with the recording position.

It is to be understood, however, that the present device is not limited to such use but may be embodied in other apparatus for different purpose and for operation upon other than manifolding material. For example, in lieu of the pin wheel unit herein illustrated, the interchangeable member may comprise a gear wheel, a type wheel, or the like.

In writing and imprinting machines, autographic registers and analogous mechanisms, it is frequently desirable to vary the position of the strip feeding unit to accommodate record material of different width or for presenting the material in different legend receiving relation to the writing or imprinting elements, or to agree with feed holes disposed in different transverse positions in the record strips to be fed.

To enable universal adaptability of the pin type feed roll herein illustrated, such roller is shown as comprising multiple sections of different lengths which may be assembled in different combinations and between any two of which the interchangeable pin wheel unit may be removably inserted. To facilitate insertion and removal of the pin wheel unit, of which any desired number may be employed simultaneously, each unit is provided with a detachable sector, the removal of which enables the pin wheel to be engaged and disengaged laterally at will between any two roll sections of the assembly. The roll sections and pin wheel units are provided with inter-engaging configurations in their adjacent faces by which upon compressive adjustment the members are interlocked in adjusted positions.

The object of the invention is to improve the 55 With the above primary and other incidental

construction as well as the means and mode of operation of pin type feeding devices whereby they may not only be economically manufactured but will be universally adaptable to feeding punched material of different width or for advancing material in different transverse paths of travel, capable of being easily and quickly interchangeably connected in different operative positions, having relatively few parts and unlikely to get out of repair.

10 A further object of the invention is to provide a sectional feed or platen roll, the separable sections of which may be assembled in various sequence and combinations to afford different spacing of multiple pin wheels or different locations of a single pin wheel axially of the assembly in interposed position between the separable sections thereof.

15 A further object of the invention is to provide a pin wheel unit or analogous element which is laterally engageable and disengageable with and from a mounting shaft.

20 A further object of the invention is to provide an assembly of roll sections and pin wheel units 25 capable of interchangeable assembly in various combinations to readily and easily accommodate the device to various conditions of use.

25 A further object of the invention is to provide a removable pin wheel or analogous element 30 and a mounting therefor with which the element is detachably engageable without the necessity of removing the mount.

30 A further object of the invention is to provide a pin wheel or analogous element and a mounting therefor with which the pin wheel is laterally engageable and disengageable.

35 A further object of the invention is to provide a pin wheel or analogous element having 40 therein a removable sector for enabling lateral engagement and disengagement with a mounting shaft.

40 A further object of the invention is to provide an adjustable mount for a pin wheel or the like 45 with which the pin wheel is laterally engageable.

45 A further object of the invention is to provide a pin type strip feeding device or analogous roller structure in which the predominating 50 element is interchangeably engageable in any one of several operative positions and which embodies the herein mentioned advantageous structural features and meritorious characteristics.

objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

Referring to the accompanying drawings, wherein is shown the preferred but obviously not necessarily the only form of embodiment of the invention,

Fig. 1 is a longitudinal sectional view of an assembled pin type platen roll having therein two relatively spaced pin wheel units.

Fig. 2 is a fragmentary exterior view of one of the pin wheel units and adjacent roll sections.

Fig. 3 is a transverse sectional view on line 3—3 of Fig. 1.

Fig. 4 is a perspective view of one of the removable pin wheel units showing the detachable sector disengaged therefrom.

Fig. 5 is an end view of one of the roll sections.

Fig. 6 is a detail perspective view of a detachably engageable type wheel embodying the present invention.

Fig. 7 is a similar view of the present invention applied to a gear wheel.

Figs. 8 and 9 are perspective views of a sectional wheel in assembled and separated condition, respectively.

Like parts are indicated by similar characters of reference throughout the several views.

In Fig. 1 there is shown a platen roll for use in a typewriter, imprinting or tabulating machine or the like comprising a plurality of separable and interchangeable roll sections 1—1—1 assembled in axial alignment upon a supporting shaft 2 mounted in a suitable frame or carriage, of which fragmentary portions 3—3 are shown. There may be any number of the roll sections 1, which are preferably of assorted lengths, but of the same diameter. They may be interchangeably assembled upon the shaft 2 in different sequence or combinations as may be found necessary to properly locate or space the detachable pin wheel or other operative elements which are positionable between any two roll sections 1.

Each of the roll sections 1 comprises a tubular core 4, which may be of metal, fiber, molded plastic, or any other suitable material. Tightly pressed or otherwise secured in each end of the core 4 is a head 5. The terminals of the tubular core 4 are preferably recessed or rabbeted as at 6 to receive the heads 5. Peripherally surrounding the tubular core 4 of each section is a surface covering 7 of rubber, composition, fiber, or other surfacing material suitable for the particular operation to be performed. The terminal faces of the roll section heads 5 are concaved or recessed as indicated at 8 and in each recessed or concave face there is provided a circular groove 9 concentric with the shaft 2. The registering concavities or recesses in contiguous faces of succeeding roll sections afford expansible and contractable chambers or compartments within which the interchangeable pin wheel or other element are demountably engageable.

The pin wheel units shown at 10 each comprises a disc 11, from the periphery of which projects radially disposed circumferentially spaced feeding pins 12, which are engageable in longitudinally spaced feed holes in a strip of material to be advanced. Each pin wheel or other interchangeable unit is provided with a detach-

able sector 13, which may have either parallel or divergent sides and which is of a width at least equal to the diameter of the shaft 2 on which the unit is to be mounted. The sector 13 is provided with ribs or splines 14 on each side slidingly engageable in grooves or ways 15 in the sides of the slots 16 left in the pin wheel or other interchangeable elements by removal of the sector 13.

The opposite faces of the pin wheel or other interchangeable unit are formed with concentric ribs or beads 17, portions of which continue across the removable sector 13, and which agree in contour and diameter with the grooves 9 in the terminal faces of the roll sections 1. The concentric projecting ribs 17 seat within the grooves or channels 9 in the heads of contiguous roll sections and are held in interlocking assembled relation therewith by axial adjustment of the roll sections 1 under compression.

The shaft 2 carries at its opposite ends abutment heads 19 and 20, one of which, 19, is fixedly pinned or otherwise secured to the shaft 2. The opposite head 20 is free for axial sliding adjustment upon the shaft under influence of a compression collar 21 screw threaded upon a collar 22 fixedly engageable in the shaft in any position of longitudinal adjustment by a set screw 23. By retractive adjustment of the screw threaded collar 21 the axial pressure upon the roll sections 1 may be relieved and sufficient clearance afforded to permit retraction of the adjustable pressure head 20 and corresponding axial adjustment of the several roll sections 1—1 relative one to another. This enables the roll sections to be separated a sufficient distance to disengage the annular ribs 17 of an interposed pin wheel or other interchangeable element from the circular grooves or channels 9 in the adjacent roll section heads. This relative adjustment also unlocks the removable sector 13 of the interposed wheel unit. When the roll sections are in interengaging relation with the interposed wheel unit the continuing rib segment 17a on the removable sector 13, which also seats within the grooves or channels 9 of the roll section heads, serves to lock the sector 13 against removal.

The axial pressure upon the sections 1 having been relieved and the sections separated, the sector 13 may be radially withdrawn entirely from the slot 16 in the wheel unit 11, whereupon the wheel unit itself may be withdrawn from between the adjacent roll sections 1 in the opposite direction from the shaft 2. The bottom of the slot 16, which is contoured to agree with the periphery of the shaft 2, the remainder of which bearing is formed in the inner end of the sector 13, carries a key or spline 24 engageable in the keyway 25 of the shaft 2 in any of the several positions in which the wheel unit may be engaged.

Having been thus removed from the assembly, the roll sections 1 may be variously shifted one relative to another to separate the assembly between any two selected sections for reception of the wheel unit 11 therebetween. To reengage the wheel unit 11 in the newly selected position is only necessary to slide the wheel 11 between the ends of the separated roll sections 1 by causing it to straddle the shaft 2 within the slot 16 until the key or spline 24 engages in the keyway 25 of the shaft and the concentric locking rib 17 is in registry with the groove or channel 9 of the adjacent roll section heads. The disengaged sector 13 is then returned slidingly within the

slot 16 until its ribs 17a agree with the ribs 17 of the wheel 11 and also register with the groove or channel 9 of the roll section head. Thereupon, by pressing the roll section 1 together axially and locking them under compression by adjustment of the screw threaded compression collar 21, the reengaged wheel 11 and its detachable sector are again locked in the newly selected position.

While, as before mentioned, the invention is especially applicable to strip feeding apparatus, there is shown in Fig. 6 a type wheel engageable and disengageable intermediate succeeding sections of the roll in exactly the same manner as the pin wheel unit. Likewise, in Fig. 7 there is shown a gear wheel also having a removable sector and which may be substituted for the pin wheel unit or for the type wheel. While the provision of corresponding ribs and grooves or channels 17 and 9 upon the wheel element and the head of the adjacent roll section 1 is a convenient method of locking the wheel in position and locking the removable sector 13 in its assembled relation with the wheel 11, other means may be provided, as for example, a series of studs or projections 18 on the wheel element engageable in corresponding holes in the roll head, as in Fig. 6, or the relation of such interengaging parts may be reversed, the rib or head 17 being formed on the head of the roll section and the corresponding groove or channel 9 formed in the wheel element. Likewise, in lieu of a relatively narrow sector slideable in a corresponding recess in the wheel, the wheel may be variously divided into segments of greater or less extent capable of assembly about the supporting shaft as shown in Figs. 8 and 9.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A pin type platen for a writing machine wherein the pin carrying element with which marginally punched series connected stationery is engaged for intermittent step by step advancement past a writing position is interchangeably engageable in different positions throughout the length of the platen, including a plurality of platen sections of different length arranged end to end and capable of transposition into different sequence, a supporting shaft upon which the platen sections are slidably adjustable one relative to another, a pin wheel unit including a removable sector, the remaining portion of which on removal of the sector is engageable in straddle relation with the shaft intermediate any two adjacent platen sections and upon restoration forming a complete pin wheel unit therebetween,

registering tongue and groove configurations upon the contacting faces of the wheel unit including the removable sector thereof and upon the contiguous platen sections interengageable upon approach of the platen sections toward the pin wheel unit to lock the removable pin wheel sector in adjusted position and the pin wheel unit in relatively fixed relation with the platen, and axial compression means for compressing the platen sections axially one against another and against the interposed pin wheel unit.

2. A pin type platen for a writing machine wherein the pin carrying member with which marginally punched series connected stationery is engaged for intermittent step by step advancement past a writing position is interchangeably engageable in different axially spaced positions, including a supporting shaft, a plurality of separable interchangeable platen sections mounted thereon for axial adjustment one relative to another, a pin wheel, including separable complementary segments insertable edgewise between selected adjacent platen sections into concentric relation therewith, matching configurations upon the contiguous faces of the platen sections and pin wheel segments, and means for axially compressing the platen sections with the pin wheel segments therebetween.

3. A pin type platen for a writing machine with which marginally punched series connected stationery is engaged for intermittent step by step advancement past a writing position including a plurality of relatively adjustable platen sections, a shaft upon which the platen sections are axially adjustable one relative to another, and a segmental pin wheel the complementary segments of which are engageable intermediate contiguous sections of the platen in concentric relation with the shaft, and adjusting means for axially compressing the platen sections upon the interposed wheel segments and for holding said parts in adjusted relation.

4. A pin type platen for a writing machine with which marginally punched series connected stationery is engaged for intermittent step by step advancement past a writing position comprising a plurality of relatively adjustable sections, a shaft on which the platen sections are axially adjustable one relative to another, and a segmental pin wheel the complementary segments of which are insertable between adjacent terminal faces of succeeding platen sections, and matching configurations upon the contiguous faces of the platen sections and inserted pin wheel segments for interlocking the pin wheel segments with the platen sections in concentric relation with the shaft, and means for axially adjusting the platen sections into interengaging relation with the interposed pin wheel segments.

5. A platen roll for use in a writing machine separable on relatively spaced transverse planes throughout its length, and a pin wheel element with which marginally punched series connected stationery is engaged for intermittent step by step advancement past a writing position insertable within the body of the platen roll intermediate the ends thereof coincident with any one of the planes of separation in concentric relation therewith, and means for interengaging the platen roll and inserted pin wheel element in assembled relation.

6. A platen roll for use with a writing machine comprising a succession of separable roll sections of different lengths capable of interchangeable assembly in different sequence and a pin wheel

element with which marginally punched series connected stationery is engaged for intermittent step by step advancement past a writing position insertable intermediate any two adjacent roll sections in concentric relation therewith, and means for retaining the roll sections and interposed pin wheel element in assembled relation.

7. A platen roll for use with a writing machine including at least a pair of axially adjustable sections, a shaft on which the platen roll sections are slidably adjustable, a pin wheel with which marginally punched series connected stationery is engaged for intermittent step by step advancement past a writing position laterally engageable with the shaft intermediate the platen roll sections including a peripherally recessed main portion adapted to straddle the shaft, a complementary removable segment engageable in the recess of the main portion, interengaging configurations upon the adjacent faces of the platen roll sections and the interposed pin wheel, and means for axially compressing the platen roll sections and interposed pin wheel.

8. A pin type platen roll for a writing machine with which marginally punched series connected stationery is engaged for intermittent step by step advancement past a writing position including a pair of axially adjustable sections, a supporting shaft on which the roll sections are mounted for relative adjustment toward and from each other, and a pin wheel demountably engageable between the sections including separable sectors insertable edgewise between the roller sections, matching configurations on the contiguous faces of the roll sections and the wheel sectors interengaging with each other, and retaining means for holding the roll sections and interposed pin wheel in assembled relation.

9. In a pin type platen roll for a writing machine in which the pin wheel element with which marginally punched series connected stationery is engaged for intermittent step by step advancement past a writing position may be assembled in any one of several axially spaced positions, a plurality of separable interchangeable roll sections of different length, capable of being transposed in different sequence, a pin wheel element insertable edgewise between any two contiguous roll sections into concentric relation therewith, and retaining means for holding the roll sections and interposed pin wheel in assembled relation.

10. A pin type platen roll for a writing machine constructed and arranged for insertion of a pin wheel element into concentric relation therewith at a given point intermediate the ends of the roll, and a pin wheel member with which marginally punched series connected stationery is engaged for intermittent step by step advancement past a writing position including a removable sector by removal of which the insertion of the pin wheel into the body of the roll is facilitated, and configurations on the opposite faces of the pin wheel member including the removable sector thereof for interengaging relation with contiguous portions of the roll structure.

11. A platen roll for a recording apparatus, including a shaft, a series of concentric platen roll sections mounted in axial alignment upon the shaft for to and fro adjustment one relative to another, and a radially slotted pin wheel section insertable between any two adjacent platen roll sections into concentric relation therewith and with the shaft without removal of any one or more platen roll sections from the shaft, and means for temporarily securing the pin wheel in its adjusted position.

12. A platen roll for a recording apparatus, including a series of unitary cylindrical platen roll sections axially adjustable into and out of abutting relation and enabling optionally located intermediate spaces therebetween upon separation of adjacent sections, and a pin wheel unit insertable in an intermediate space between any two adjacent roll sections upon separation thereof, and means for securing the roll sections in axially adjusted relation with an inserted pin wheel clamped therebetween.

13. A platen roll for a recording apparatus, including a series of axially aligned platen roll sections and at least one pin wheel unit removably interposed between succeeding platen roll sections of the series, said platen roll sections being relatively adjustable while maintaining their axial alignment to permit transposition of the pin wheel into other positions between different platen roll sections of the series.

14. A platen roll for a recording apparatus, including a shaft, a series of aligned axially adjustable platen roll sections relatively adjustable toward and from each other upon the shaft, a sectional pin wheel unit optionally insertable between any two platen roll sections in concentric relation therewith and with the shaft, matching configurations upon the abutting faces of the pin wheel sections and adjacent platen roll sections preventing removal of the pin wheel unit until the platen roll sections are axially adjusted away therefrom, and means for releasably maintaining the platen roll sections and interposed pin wheel in assembled relation.

15. A platen roll for a recording apparatus, including a pair of unitary cylindrical platen roll sections disposed in concentric relation and axially adjustable one relative to the other, a shaft upon which the sections are mounted, a sectional pin wheel unit interposed between the platen roll sections comprising a sector removably engageable in straddle relation with the shaft intermediate the platen roll sections and a complementary matching segment of the pin wheel also insertable between the platen roll sections and forming with the initial sector a complete pin wheel unit, means for preventing separation of the pin wheel portions when in adjusted relation between the platen roll section, and means for preventing separation of the platen roll sections when in adjusted relation relative to the intermediate pin wheel unit.
